DISPENSING DEVICE FOR TAPE HOLDER OF THE SPOOL TYPE

Vincent F. Slezak, Berwyn, Ill.

Application July 13, 1953, Serial No. 367,462

1 Claim. (Cl. 164—84.5)

The invention relates to new and useful improvements in a tape dispensing device and more particularly a tape dispensing device for tape holders of a spool type.

An object of the invention is to provide a spool tape holder with a tape dispensing device wherein the tape when ready for severing is laid over a plate and is clamped thereagainst by a cutting blade to facilitate the severing of the tape by a pull thereon across the blade.

Another object of the invention is to provide a tape dispensing device of the above type wherein the plate against which the tape end is pressed for severing may be swung from between the flanges of the spool so that the tape is made readily accessible for the next stripping operation.

A still further object of the invention is to provide a supporting member for the cutting blade with the means for preventing the retained end portion of the severed tape from sticking to said blade supporting member.

In the drawings which show by way of illustration one embodiment of the invention:

Figure 1 is a vertical sectional view taken between the flanges of a spool tape holder with the improved dispensing device applied thereto and also shown in section;

Figure 2 is a sectional view on the line 2, 2 of Figure 1;

Figure 3 is a sectional view on the line 3, 3 of Figure 1;

Figure 4 is a view showing the dispensing device in top plan.

In my copending application, Ser. No. 367,440, filed July 13, 1953 we have shown a tape dispensing device for a tape roll wherein the end portion of the tape which has been stripped from the roll is laid over a supporting plate and clamped thereto by a cutting blade to facilitate the severing of the tape by a pull thereon across the blade. The present invention has to do with a tape dispensing device for a spool type of holder wherein the dispensing tape is clamped for severing in the same manner as in my copending application. Referring in detail to the present illustrated embodiment of the invention the dispensing device is shown as applied to a tape holder of the spool type which includes a central supporting member or hub 1 preferably of metal. Radially extending outwardly over the ends of this supporting member are spaced flanges 2, 2. The supporting member is provided with outwardly extending ribs 3, 3 against which the flanges 2, 2 abut and the extreme outer ends 4, 4 of the supporting member 1 are turned outwardly so as to clamp the flanges between the rib and this outwardly turned member. The flanges are rolled outwardly at their peripheral edge into a hollow reenforcing bead indicated at 5, 5. The tape with the adhesive on its inner face is wound spirally on a fiber sleeve 6 and this fiber sleeve 6, together with the tape roll loosely fits on the supporting member 1 so that the tape roll can rotate on this supporting member when the tape is being stripped

2

from the periphery of the roll. This tape holder referred to as spool type is very well known in the art and further description thereof is not thought necessary.

Applicant's dispensing device is attached to the flanges 5 of the spool holder. A rod 7 extends across the spool holder parallel with the axis of the tape roll and adjacent the outer peripheral edge of the flanges 2, 2. The ends of the rod are headed so as to retain it in the flanges. Mounted on this rod is a tape supporting plate 8. The 10 rear end of this plate 8 is bent around the rod so that it can pivot on the rod and swing outwardly from between the flanges. There is a second rod 9 parallel with the first rod 7 which extends through the flanges and is likewise headed so as to be retained in the flanges of the spool. The supporting plate 8 is of a length so that it overlies the rod 9 and is supported by said rod during the severing of the tape. The tape indicated at T in the drawings is led around the plate 8 and when it is desired to dispense a length of tape it is pulled on in the 15 general direction of the plate and this will lay the tape over the plate 8 which serves as a support therefor during severing. The severing blade 10 is formed integral with the plate 11 having depending lugs 12, 12 at the rear end of the plate which lugs are perforated for pivoting and the rod 7 passes through these perforations in the lugs. This plate supporting the blade 10 is free to pivot on the rod 7. When the desired length of tape has been 20 drawn from the tape roll then the plate 11 is moved in a clockwise direction so as to bring the blade 10 into engagement with the tape and press the tape against the supporting plate 8 therefor. While the tape is thus clamped tightly against the supporting plate by the blade 10 then the tape is drawn across the holding edge of the blade and thus severed.

35 After the tape has been severed and when it is desired to pull off a new length of tape the supporting plate 8 will be swung outwardly from between the flanges at its free end thus carrying the plate 11 and the blade 10 together with the severed end portion of the tape free 40 of the flanges so that the plate and blade may be separated and the tape readily grasped for drawing off a new length.

The plate 11 is provided with slits forming a tongue 13 which is bent downward into the space beneath the blade supporting plate 11 so as to prevent the tape from 45 contacting the plate 11 and adhering thereto. The blade 10 has a serrated edge 14 which aids in the cutting and rupturing of the tape for severing the drawn off end from the body portion of the tape. When the tape is severed it will cling to this serrated edge. However, if 50 it should be freed from the serrated edge the upper side which is the adhesive side will not contact the plate 11 and stick thereto.

55 From the above it is noted that the supporting plate 8 performs two functions. It serves as a means for supporting the tape for easy severing and it also serves as a means for lifting the plate supporting the severing blade so as to position the tape end for easy access. During the stripping of the tape the tape roll together with the fiber sleeve 6 will rotate freely on the supporting hub member 1 of the spool.

60 It is obvious that minor changes may be made in the details of construction without departing from the spirit of the invention as set forth in the appended claim.

I claim:

65 In a spool holder for tape having a hub on which the tape roll is mounted for rotation and flanges extending radially from the hub, the combination of a rod mounted in said flanges and extending across the holder

and spaced radially outwardly from the tape roll, a supporting plate pivotally mounted on said rod over which the tape is drawn, means carried by the flanges on which said plate rests, a blade supporting plate pivotally mounted on said rod and a blade carried by said last named plate and adapted to clamp the tape against the tape supporting plate during the severing of the tape, said blade supporting plate having a tongue depending therefrom to prevent the tape end from contacting and sticking to said plate.
